UNITED STATES PATENT OFFICE.

MAX ROBINS, OF CHICAGO, ILLINOIS.

DESIGN FOR A CARTON FOR FACE POWDER.

60,372.

Specification for Design.

Patented Feb. 7, 1922.

Application filed May 4, 1921. Serial No. 466,697. Term of patent 14 years.

To all whom it may concern:

Be it known that I, MAX ROBINS, a citizen of the United States, residing at Chicago, in the county of Cook and State of Illinois, have invented a new, original, and ornamental Design for a Carton for Face Powder, of which the following is a specification, reference being had to the accompanying drawing, forming part thereof.

In the drawings,

Figure 1 is a plan view of the carton;

Figure 2 is an end elevation; and
Figure 3 is a side elevation.

I claim:

The ornamental design for a carton for face powder, as shown.

In witness whereof I hereunto subscribe my name this 28th day of April, 1921.

MAX ROBINS

Witness:

EDNA V. GUSTAFSON.
